ADAPTIVE BUILDING SYSTEM AND PARTS**CROSS-REFERENCE TO RELATED APPLICATION**

This application claims priority to U.S. Provisional Application No. 63/607,866, filed Dec. 8, 2023, which is herein incorporated by reference in its entirety.

FIELD OF THE INVENTION

The field of the subject matter is an adaptive building system for, for example, human occupancy or storage. For example, in some embodiments, the invention relates to a modular, expandable and changeable building system for housing of humans or animals, office space and/or storage.

BACKGROUND OF THE INVENTION

Prefabricated buildings, including houses and storage buildings, are currently available today. Prefabricated houses are typically constructed at a manufacturing site and then transported and assembled at a building site. These houses are typically designed and constructed in a variety of floor plans. These plans, however, are only minimally adaptable by the customer.

Another form of prefabricated houses are manufactured homes, which can also be known as a double wide. The layout of a double wide is typically restricted to the prebuild design and cannot be adapted by the customer. Still another type of prefabricated house is panelized constructions. Panelized construction is where house panels are finished in a factory and transported to a building site. Similar products are available for storage buildings.

There is a need for an adaptive building system. For example, there is a need for housing, office space and/or storage space which can be adapted to a customer selected layout either at the time of the original build or at a later time.

SUMMARY OF THE INVENTION

These and other needs are addressed by the various aspects, embodiments, and configurations of the present disclosure.

In Example 1, a building module system includes a building module, which includes a base support, a plurality of wall panels and siding panels. The base support includes a frame, a subfloor, floor supports, a first bottom wing, a second bottom wing, flooring panels, a roof support ceiling panels, a first top wing, a second top wing and vertical supports. The frame has a first side, a second side, a first end and a second end. The subfloor is connected to the frame and extends from the first side to the second side and from the first end to the second end. The floor supports are positioned above the subfloor, and each floor support extends from the first side to the second side of the frame. The first bottom wing is connected to and extends upwards from the first side of the frame. The second bottom wing is connected to and extends upwards from the second side of the frame. The flooring panels are positioned above and are supported by the floor supports. Each floor panel extends from the first side to the second side of the frame and the flooring panels together extend from the first end to the second end of the frame. The roof support is spaced apart from the base support and has a first side, a second side, a first end and a second end. The ceiling panels are attached to the roof

support. The first top wing is connected to and extends downward from the first side of the roof support. The second top wing is connected to and extends downward from the second side of the roof support. The vertical supports extend vertically between the base support and the roof support. The plurality of wall panels are connected to the frame and extend from the flooring panels to the ceiling panels, the ceiling panels, floor panels and wall panels creating an interior space of the building module. The siding panels are attached to and extend from the first top wing to the first bottom wing and from the second top wing to the second bottom wing. The siding panels create an exterior surface of the building module.

In Example 2, the building module system of Example 1 wherein the wall panels include at least a first wall panel and a second wall panel and each of the first wall panel and the second wall panel include an interior panel having a top interior panel edge, a bottom interior panel edge, a first side interior panel edge and a second side interior panel edge; a first insulating panel connected to the interior panel, the first insulating panel having a top first insulating panel edge aligned with the top interior panel edge, a bottom first insulating panel edge aligned with the bottom interior panel edge, a first side first insulating panel edge aligned with the first side interior panel edge and a second side first insulating panel edge aligned with the second side interior panel edge; and a second insulating panel connected to the first insulating panel, the second insulating panel having a top second insulating panel edge aligned with the top first insulating panel edge, a bottom second insulating panel edge aligned with the bottom interior panel edge, a first side second insulating panel edge not aligned with the first side first insulating panel edge and forming a protrusion, and a second side second insulating panel edge not aligned with the second side first insulating panel edge and forming a notch, wherein the protrusion of the first wall panel fits within the notch of the second wall panel and a portion of the first wall panel overlaps with a portion of the second wall panel.

In Example 3, the building module system of Example 2 wherein the protrusion of the first wall panel fits within the notch of the second wall panel and a portion of the first wall panel overlaps with a portion of the second wall panel.

In Example 4, the building module system of Example 3 and further including a panel connecting support connected to the second insulating panel of the first wall panel and the second insulating panel of the second wall panel.

In Example 5, the building module system of Example 2 wherein the first wall panel and the second wall panel are removable in whole.

In Example 6, the building module system of Example 2 wherein a window or a door is positioned within the first wall panel and is in communication with the interior panel, the first insulating panel and the second insulating panel.

In Example 7, the building module system of Example 1 and further comprising a rafter module connected to the roof support. The rafter module includes a plurality of webs spaced apart from one another and extending in a first direction, the webs having a top surface, a bottom surface, a first end and a second end; a plurality of chords spaced apart from one another and extending in a second direction perpendicular to the first direction, the plurality of chords connected to the top surface of the webs; and a bottom chord connected to the bottom surface of the webs at the second end, the bottom chord creating a slope so that the second ends of the webs are higher than the first ends of the webs.

In Example 8, the building module system of Example 7 and further comprising a plurality of rafter modules connected to one another.

In Example 9, the building module system of Example 1 and further including a second building module connected to the building module.

In Example 10, a method of building a building module for human occupancy, the method including building a base support, connecting a plurality of wall panels to the frame, and connecting a plurality of siding panels to and extending from the first top wing to the first bottom wing and from the second top wing to the second bottom wing, the siding panels creating an exterior surface of the building module. The base support includes a frame having a first side, a second side, a first end and a second end; a subfloor connected to the frame and extending from the first side to the second side and from the first end to the second end; floor supports positioned above the subfloor, each floor support extending from the first side to the second side of the frame; a first bottom wing connected to and extending upwards from the first side of the frame; a second bottom wing connected to and extending upwards from the second side of the frame; flooring panels positioned above and supported by the floor supports, each floor panel extend from the first side to the second side of the frame and the flooring panels together extending from the first end to the second end of the frame; a roof support spaced apart from the base support and having a first side, a second side, a first end and a second end; ceiling panels attached to the roof support; a first top wing connected to and extending downward from the first side of the roof support; a second top wing connected to and extending downward from the second side of the roof support; and vertical supports extending vertically between the base support and the roof support. The wall panels extend from the flooring panels to the ceiling panels. The ceiling panels, floor panels and wall panels creating an interior space of the building module.

In Example 11, the method of Example 10, wherein all lumber used is standard size lumber.

In Example 12, the method of Example 10, wherein each wall panel can be removed as a single unit.

In Example 13, the method of Example 10, wherein each flooring panel can be removed as a single unit.

In Example 14, the method of Example 10 and further comprising connecting the base support to a second base support.

In Example 15, the method of Example 10 wherein building the base support is accomplished without cutting lumber.

In Example 16, the method of Example 10 wherein the wall panels include at least a first wall panel and a second wall panel, and each of the first wall panel and the second wall panel include: an interior panel having a top interior panel edge, a bottom interior panel edge, a first side interior panel edge and a second side interior panel edge; a first insulating panel connected to the interior panel, the first insulating panel have a top first insulating panel edge aligned with the top interior panel edge, a bottom first insulating panel edge aligned with the bottom interior panel edge, a first side first insulating panel edge aligned with the first side interior panel edge and a second side first insulating panel edge aligned with the second side interior panel edge; and a second insulating panel connected to the first insulating panel, the second insulating panel having a top second insulating panel edge aligned with the top first insulating panel edge, a bottom second insulating panel edge aligned with the bottom interior panel edge, a first side second

insulating panel edge not aligned with the first side first insulating panel edge and forming a protrusion, and a second side second insulating panel edge not aligned with the second side first insulating panel edge and forming a notch, wherein the protrusion of the first wall panel fits within the notch of the second wall panel and a portion of the first wall panel overlaps with a portion of the second wall panel.

In Example 17, the method of Example 16 and further including removing the first wall panel to form an opening; and connecting the base support to a second base support at the opening.

In Example 18, the method of Example 16 and further comprising repairing the first wall panel by disconnecting the first wall panel from the second wall panel, removing the first wall panel from the frame, repairing the first wall panel and reconnecting the first wall panel to the frame.

In Example 19, the method of Example 10 and further including connecting a rafter module to the roof support. The rafter module including a plurality of webs spaced apart from one another and extending in a first direction, the webs having a top surface, a bottom surface, a first end and a second end; a plurality of chords spaced apart from one another and extending in a second direction perpendicular to the first direction, the plurality of chords connected to the top surface of the webs; and a bottom chord connected to the bottom surface of the webs at the second end, the bottom chord creating a slope so that the second ends of the webs are higher than the first ends of the webs.

In Example 20, An adaptive wall system for a building module, the adaptive wall system including a first wall panel and a second wall panel. Each of the first wall panel and the second wall panel having: an interior panel having a top interior panel edge, a bottom interior panel edge, a first side interior panel edge and a second side interior panel edge; a first insulating panel have a top first insulating panel edge aligned with the top interior panel edge, a bottom first insulating panel edge aligned with the bottom interior panel edge, a first side first insulating panel edge aligned with the first side interior panel edge and a second side first insulating panel edge aligned with the second side interior panel edge; and a second insulating panel having a top second insulating panel edge aligned with the top first insulating panel edge, a bottom second insulating panel edge aligned with the bottom interior panel edge, a first side second insulating panel edge not aligned with the first side first insulating panel edge and forming a protrusion, and a second side second insulating panel edge not aligned with the second side first insulating panel edge and forming a notch, wherein the protrusion of the first wall panel fits within the notch of the second wall panel and a portion of the first wall panel overlaps with a portion of the second wall panel.

BRIEF DESCRIPTION OF THE DRAWINGS

The accompanying drawings are incorporated into and form a part of the specification to illustrate several examples of the present disclosure. These drawings, together with the description, explain the principles of the disclosure. The drawings simply illustrate preferred and alternative examples of how the disclosure can be made and used and are not to be construed as limiting the disclosure to only the illustrated and described examples. The drawings may not be to scale. Further features and advantages will become apparent from the following, more detailed, description of the various aspects, embodiments, and configurations of the disclosure, as illustrated by the drawings referenced below.

FIG. 1 is a photograph of an exemplary building module.

- FIG. 2 is a perspective view of a building module.
 FIG. 3 is a perspective view of a frame support.
 FIG. 4 is a perspective view of the frame support of FIG. 2 and including a flooring module.
 FIG. 5 is an enlarged perspective view of a floor frame support.
 FIG. 6 is a perspective view of a roof.
 FIG. 7 is an exploded view of a roof.
 FIG. 8 is a front view of a wall panel.
 FIG. 9 is a back view of the wall panel of FIG. 7.
 FIG. 10 is a perspective view of adjacent wall panels.
 FIGS. 11-14 are schematic top view diagrams of exemplary configurations with multiple building modules.

DETAILED DESCRIPTION

The present disclosure provides a new adaptive and changeable building module system which allows pieces of a building to be moved or relocated with ease either at the time of the original build or at a later time. The present system can be used to construct housing buildings, office buildings and storage buildings. The building modular system is comprised of one or more modular units which can be configured in a variety of orientations, allowing unique floorplans and layouts such as L-shaped, squares with an inner court yard and long rectangular shapes, just to name a few. The adaptive building system can be constructed with building materials available at common retail or home improvement stores, removing the need for a customer to purchase specialty parts from a specific retailer or cut lumber.

FIG. 1 is a photograph of exemplary building module 10 which includes first end wall 12, first side wall 16 and roof 20 which together with second end wall 14, second side wall 18 and flooring panels 71 (See FIG. 2) form an enclosed structure. Building module 10 can include one or more doors 13, which can be positioned within one of the walls, such as first end wall 12. Building module 10 can also include one or more windows 15, which can be positioned within one of the walls, such as first side wall 16. Building module 10 can be attached to a carriage which includes wheels 21. Wheels 21 allow building module 10 to be moved.

FIG. 2 is a perspective view of building module 10 in which portions of building module 10 have been removed to show detail inside the structure. Building module 10 includes first end wall 12, second end wall 14, first side wall 16, second side wall 18 and roof 20. First end wall 12 and second end wall 14 are opposite each other and form two of the four walls of building module 10. First end wall 12 and second end wall 14 are the same shape and size. First side wall 16 and second side wall 18 are also opposite each other and form the other two walls of building module 10. First side wall 16 and second side wall 18 are the same shape and size. Roof 20 is attached to the top of first end wall 12, second end wall 14, first side wall 16, second side wall 18 and roof 20 and together these components create an enclosed rectangular living space.

In some embodiments, siding 22, such as steel siding or steel paneling, can be attached to the outside of first end wall 12, second end wall 14, first side wall 16 and second side wall 18 to provide an exterior surface and protection of the living space from the outdoor elements. Siding 22 is designed to allow adjustment. In some embodiments, roof 20 can include covering 24 to protect the top of building module 10 from the outdoor elements. Suitable coverings include steel sheets or shingles, such as asphalt shingles. As discussed herein, first end wall 12, second end wall 14, first

side wall 16 and/or second side wall 18 can include various additional elements, such as doors and/or windows. In some embodiments, building module 10 has outer dimensions of about 8 feet in width and 24 feet long and has about 8 foot high ceilings inside. As explained herein, these dimensions are obtained by using commonly commercially available materials and little to no additional cutting of lumber is required for assembly.

- FIG. 3 is a perspective view of frame support 25 which includes roof support 26 (having lengthwise roof supports 30 and 32 and cross supports 34 and 36), base support 40 (having lengthwise base supports 42 and 44 and cross supports 46 and 48), vertical supports 50a, 50b, 52a, 52b, 54a, 54b, 56a and 56b, vertical panels 50c, 52c, 54c and 56c and floor supports 55a and 55b. Roof support 26 includes lengthwise roof supports 30 and 32 which run the length of building module 10 and cross supports 136, 138, 140, 142, 144 (shown in FIG. 7) which extend perpendicular to lengthwise roof supports 30 and 32. In some embodiments, lengthwise roof supports 30 and 32 are 2x12 boards available from a commercial lumber yard which are 24 feet in length. That is, lengthwise roof supports can be about 24 feet in length, 12 inches wide and 1.5 inches thick.
- Cross supports 34 and 36 attach to the ends of lengthwise roof supports 30 and 32. In some embodiments, cross supports 34 and 36 connect to lengthwise roof supports 30 and 32 at basic butt joints and lengthwise roof supports 30 and 32 cover the ends of cross supports 34 and 36.
- Base support 40 includes lengthwise base supports 42 and 44 which run the length of building module 10 and cross supports 46 and 48 which extend perpendicular to lengthwise base supports 42 and 44. In some embodiments, lengthwise base supports 42 and 44 are 2x12 boards available from a commercial lumber yard which are 24 feet in length. That is, lengthwise base supports can be about 24 feet in length, 12 inches wide and 1.5 inches thick. In some embodiments, cross supports 46 and 48 can be 6x6 boards that are 8 feet in length.

Cross supports 46 and 48 attach to the ends of lengthwise base supports 42 and 44. In some embodiments cross supports 46 and 48 connect to lengthwise base supports 42 and 44 at basic butt joints and lengthwise base supports 42 and 44 cover the ends of cross supports 46 and 48.

Vertical supports 50a, 50b, 52a, 52b, 54a, 54b, 56a and 56b form the corners of frame support 25 and connect base support 40 and roof support 26. Vertical supports 50a, 50b, 52a, 52b, 54a, 54b, 56a and 56b extend upwards from the corners of base support 40. Vertical supports 50a and 50b form a first corner, vertical supports 52a and 52b form a second corner, vertical supports 54a and 54b form a third corner and vertical supports 56a and 56b form a fourth corner. In some embodiments, vertical supports 50a, 50b, 52a, 52b, 54a, 54b, 56a and 56b can be 8 feet in length. Vertical supports 50a, 50b, 52a, 52b, 54a, 54b, 56a and 56b transfer weight from roof support 26 to base support 40. Additional vertical supports may be added to increase roof support or even stacking of multiple building modules.

Vertical panels 50c, 52c, 54c and 56c are positioned over vertical supports 50b, 52b, 54b and 56b. One end of vertical panel 54c is flush with the edge of cross support 34 and the opposite end of vertical panel 54c is flush with the edge of cross support 46. Vertical panels 50c, 52c, 54c and 56c connect roof support 26 to base support 40 and helps prevent sideways movement. In one embodiment, vertical panels 50c, 52c, 54c and 56c can be 10 feet in length so they extend from the top edge to the bottom edge of building module 10.

Floor supports **55a** and **55b** extend between lengthwise base supports **42** and **44**. Floor supports **55a** can be 4×6 boards and floor supports **55b** can be 2×6 boards. Floor supports **55a** and **55b** can be arranged in a pattern such that floor supports **55a** are positioned every 4 four feet and floor supports **55b** are positioned every foot between adjacent floor supports **55a**. In this way, three floor supports **55b** are positioned between adjacent floor supports **55a**.

FIG. 4 is a perspective view of the base or flooring structure and including optional carriage **72**. Carriage **72** attaches to base support **40** and allows for building module **10** to be attached to a trailer, wheels or other running gear. Carriage **72** also provides additional space for utilities to run under building module **10**.

FIG. 5 is an enlarged perspective view of carriage **72**, which includes carriage supports **58** and lengthwise supports **60** and **62**. In some embodiments, lengthwise supports **60** and **62** can be spaced about 42 inches apart and can be 6×6 boards that are 24 feet in length. Lengthwise supports **60** and **62** extend between cross support **46** and **48** of base support **40**. Carriage supports **58** are perpendicular to lengthwise supports **60** and **62** and extend between lengthwise base supports **42** and **44**. Carriage supports can be 6×6 boards and can be positioned 4 feet apart along the length of building module **10**. In some embodiments, carriage **72** can be built first and building module **10** can be built onto existing carriage **72**. In other embodiments, carriage **72** can be added to an existing building module **10**. In this way, building module **10** can be adapted even after it is built.

The flooring structure is further shown in FIG. 4. Subfloor **70** is positioned on top of carriage supports **58**. In some embodiments, subfloor **70** can be plywood or other flat material. In some embodiments, subfloor **70** can be about half an inch thick. Next, floor supports **55a** and **55b** are positioned on top of subfloor **70**. Finally, flooring panels **71** are positioned on top of floor supports **55a** and **55b**. In some embodiments, subfloor **70** can be plywood, such as 3/4 inch thick plywood. Insulation can be positioned between subfloor **70** and flooring panels **71**. For example, insulation can be blown in between subfloor **70** and flooring panels **71**. This structure allows the floor to be accessed from inside building module **10** and/or from underneath building module **10**.

In use, if carriage **72** is present, carriage **72** can sit on a foundation, such as concrete blocks, or a platform or slab. If carriage **72** is not present, base **40** can sit on a foundation, such as concrete blocks, or a platform or slab. In some embodiments, additional insulation can be added to carriage **72**. In other embodiments, insulation can be connected to the underside of the subfloor with or without the use of carriage **72**.

FIG. 6 is a perspective view of a portion of roof **20** with siding **22** and covering **24** removed to show roof support **26** and rafter **128**. Roof support **26** supports rafter **128** and connects rafter **128** to the remainder of building module **10**. Additional cross supports **138-144** can be positioned between lengthwise roof supports **30** and **32** as shown in exploded view FIG. 7. In some embodiments, cross supports **134-144** can be 2×4 boards and 2×12 boards. For example, 2×4 boards can be positioned every 1 foot between 2×12 boards. And 2×12 boards can be positioned every 4 feet. In this way, a trough is formed between adjacent 2×12 boards while support is given by the 2×4 boards to the overhead structure.

Rafter **128** is formed from one or more rafter modules **129**, which are formed by top chords, such as first top chord **148**, second top chord **150**, third top chord **152**, fourth top chord **154** and fifth top chord **156**, webs, such as webs

158-166, and bottom chord **168**. Top chords **148-156** run the length of building module **10**. In some embodiments, top chords **148-156** can be about 8 feet in length. In some embodiments, top chords **148-154** can be 2×4 boards available from a lumber yard which are 8 feet in length. Top chord **156** may be the same width as or wider than the boards used for top chords **148-152**. For example, top chord **156** can be a 2×4 board or a 2×6 board available from a lumber yard which is 8 feet in length. Top chord **156** may not be flush with the ends of webs **166-158**. For example, top chord **156** may extend about 2 inches past the ends of webs **166-158**. In some embodiments, top chords **148-156** are not flush with sides of webs **158** and **166** and can hang over the side of web **158** and web **166** by 3/4-1.5 inches. In some embodiments, top chord **156** can also hang over the ends of webs **158-164** and can be connected to roof support **32**. For example, top chord **156** can overhang the ends of each of webs **158-162** by about 3/4 inch to about 1.5 inches. In some embodiments, every four feet webs **158-162** can be attached to cross supports **136** and **138**. For example, in FIG. 7, webs are attached to cross supports **140**, **142** and **144**. This can provide further stability and attachment of roof **20**.

Each of webs **158-166** span the width of building module **10** and between top chords **148-156**. Top chords **148-156** are attached to webs **158-166** for example with screws or nails. Webs **158-166** are spaced apart from one another. For example, in some embodiments, a web can be positioned along the length of top chords **148-156**. Webs **158-166** can be 2×4 boards which are turned such that the narrower side is in contact with the top chords. In some embodiments, an first end of web **158** is aligned with the outer edge of top chord **156** and the second end of web **158** is aligned with the outer edge of top chord **148**.

Top chords **148-156** are spaced apart from one another. In some embodiments, a top chord can be positioned along the length of a web. In some embodiments, a first end of a chord, such as first top chord **148** is aligned with an outer edge of web **158** and a second end of chord **148** is aligned with the outer edge of web **166**. The remaining webs and top chords may be aligned in a similar manner. In some embodiments, the top surface of the web is in contact with the top chord. For example, the top surface of webs **158-164** are in contact with the bottom surface of top chords **148-156**.

Bottom chord **168** is attached to lengthwise roof support **30** and to the second ends of webs **158-166**. Bottom chord **168** elevates the second ends of webs **158-166** to create a sloped rafter **128**. For example, the thickness of bottom chord **168** may be selected such that rafter **128** has a 12×1 slope. Bottom chord **168** can be formed from one or more 2×4 boards. If more than one more is used, the boards are stack on top of one another to form thickness of bottom chord **168** and the distance between second ends of webs **158-166** and lengthwise roof support **30**. In some embodiments, bottom chord **168** is the same length as top chord **148**. The bottom chord **168** is in contact with the bottom surface of the webs. For example, the top surface of bottom chord **168** is in contact with the bottom surface of webs **158-164**.

Rafter **128** may include one or more rafter modules **129** depending on the length of rafter **128**. Rafter modules **129** are positioned adjacent to one another on roof support **26** such that rafter modules **129** extend the length of roof support **26**. Top chord **156** can be connected to lengthwise roof support **32** for example by screws or nails and bottom chord **68** can be connected to lengthwise roof support **30** for example by screws or nails. A roof covering material, such

as steel sheeting, can be attached to top chords 148-156 to protect rafters 128 and create an enclosed building module 10.

Plywood or other flat surface can be attached to the bottom of rafter 128 to form the ceiling in building module 10. For example, plywood can be positioned to form ceiling panels on the bottom of rafters 128. In some embodiments, insulation can be positioned in the rafters 128 and the plywood keeps the insulation in place.

Roof 20 is formed from supplies readily available at a lumber or hardware store, which simplifies the construction and reduces costs. Roof 20 can be quickly constructed and attached to building module 10. Additionally, roof 20 is designed to allow the user to change the configuration of multiple building module 10. For example roof 20 allows multiple building modules 10 to be arranged end to end to form a long rectangle configuration (see FIG. 12), an L-shaped building, an U-shaped building or a square building with an inner courtyard.

Roof 20 can be formed using one or more rafters 128. In some embodiments, each rafter 128 can be built and then installed as a single unit. Additionally, each rafter 128 can be removed as a single unit. That is, rafter 128 can be removed in whole. For example, if a building module included three rafters and the middle rafter was damaged, the middle rafter could be removed as a single unit leaving the rafters on either side in place. The middle rafter could then be repaired and set back into place. If the rafter could not be repaired, a new rafter could be positioned in its place.

FIG. 8 is a front view and FIG. 9 is a back view of wall panel 200, which includes interior panel 202, first insulation panel 204, second insulation panel 206, panel support 208 and panel connecting support 210. Interior panel 202, first insulation panel 204 and second insulation panel 206 have the same height (measured from top edge 212 to bottom edge 214) and width (measured from first side edge 216 to second side edge 218). Interior panel 202, first insulation panel 204 and second insulation panel 206 form a sandwich construction.

Interior panel 202 faces into building module 10. In some embodiments, interior panel 202 is a finished surface and is the exposed wall surface on the inside of building module 10. In other embodiments, interior panel 202 can be further finished or painted. Interior panel 202 can be a wood laminate or plywood.

First insulation panel 204 is directly adjacent to interior panel 202. First insulation panel 204 and interior panel 202 are aligned along top edge 212, bottom edge 214, first side edge 216 and second side edge 218. First insulation panel 204 provides insulation to building module 10. In some embodiments, first insulation panel 204 is a closed-cell extruded polystyrene foam (XPS), such as Styrofoam^{TM}, panel. The thickness of insulation panel 204 can vary depending, for example, on the amount of insulation desired. In some embodiments, first insulation panel 204 is about 1.5 inches thick.

Second insulation panel 206 aligns with first insulation panel 204 at top edge 212 and bottom edge 214 of wall panel 202. Second insulation panel 206 does not align with first insulation panel 204 at first side edge 216 or second side edge 218 such that second insulation panel 206 is offset from first insulation panel 204. For example, the offset can form a notch or step at one side of wall panel 202 and a protrusion or step at the other side of wall panel 202. Second insulation panel 206 can be a XPS panel. The thickness of insulation panel 206 can vary depending, for example, on the amount of insulation desired. In some embodiments, first

insulation panel 204 is about 1.5 inches thick. While two insulation panels are show in FIG. 8 and FIG. 9, in some embodiments, wall panel 200 can contain more than two insulation panels.

5 Panel support 208 provides support to wall panel 200. In some embodiments, panel support 208 is 2x4 board.

Panel connecting support 210 also extends from top edge 212 to bottom edge 214 and provides support to wall panel 200. Additionally, panel connecting support 210 extends from first side edge 216 and can be used to connect two adjacent wall panels 200. For example the portion of panel connecting support 210 which extends from first side edge 216 can overlap onto an adjacent wall panel and thus can be connected to an adjacent wall panel using fasteners such as screws or nails. In some embodiments, panel connecting support 210 is a 2x4 or 2x6 board. The boards can vary in size. For example, thicker boards can be used to provide more room to run utilities.

FIG. 10 is a perspective view showing to adjacent wall panels 200a and 200b. The offset of second insulation panels 206a and 206b forms a step in wall panels 200a and 200b into which the adjacent wall panel fits. As shown in FIG. 10, a step is formed along first side edge 216b of wall panel 200b because second insulation panel 206b is offset from first insulation panel 204b. First insulation panel 204a and interior panel 202a fit within this step. In this way, an air seal is formed in walls formed by wall panels 200. Additionally, because the insulation panels extend the full length of each wall, there is no thermal bridging and there is continual insulation along the entire length of each wall.

20 Wall panels 200a and 200b can be attached to one another by panel connecting support 210b. Panel connecting support 210 helps with the air seal formed in the walls. Panel connecting support 210 also assists in making the wall 25 panels flush with each other. FIG. 10 also shows door 220 and window 222.

One or more wall panels 200 can form a wall of the building module. In some embodiments, each wall panel 200 can be built and then installed as a single unit. Additionally, 30 each wall panel 200 can be removed as a single unit. That is, each wall panel 200 can be removed in whole. For example, if a building module included three adjacent wall panels and the middle wall panel was damaged, the middle wall panel could be removed as a single unit leaving the wall panels on either side in place. The middle wall panel could then be repaired and set back into place. If the wall panel could not be repaired, a new wall panel could be positioned in its place.

45 Turning back to FIG. 2, top wing 13a and bottom wing 11a assist in connecting wall panel 200a to building module 10. Top wing 13a extends downward from lengthwise roof support 32. In some embodiments, the top edge of top wing 13a is flush with the top edge of lengthwise roof support 32 so as to form a level or flat surface. Top wing 13a is wider than lengthwise roof support 32 so that top wing 13a extends below the bottom edge of lengthwise roof support 32.

Bottom wing 11a extends upwards from lengthwise base support 44 and bottom wing 11b extends upwards from lengthwise base support 42. In some embodiments, the 50 bottom edge of bottom wing 11a is flush with the bottom edge of lengthwise base support 44 so as to form a level or flat surface. Bottom wing 11a is wider than lengthwise base support 44 so that bottom wing 11a extends above the top surface of lengthwise base support 44. A top wing and bottom wing having the same configuration are present on the opposite side of building module 10. Bottom wing 11b and lengthwise base support 42 have a similar configuration.

11

Top wing 13a and bottom wing 11a can be formed from 10 foot sections of plywood. Alternatively, they can be 8 foot sections having 16 inches in width. In some configurations, top wing 13a and bottom wing 11a extend the full length of building module 10. In other embodiments, top wing 13a and bottom wing 11a are formed from a continuous sheet of plywood. Top wing 13a and bottom wing 11a create room for utilities by creating a space between wall panel 200a and siding 22.

Floor panels 71 extend between the interior surfaces of bottom wings 11a and 11b. Floor panel 71 is supported from underneath by base support 40.

Wall panel 200a sits on top of floor panel 71. More specifically, bottom edge 214 of wall panel 200a rests on floor panel 71. Top wing 13a overlaps with a portion of wall panel 200a towards the top of wall panel 200a. Top wing 13a can be connected to wall panel 200a by fastening top wing 13a to panel support 208 and panel connecting support 210 with for example screws or nails. Bottom wing 11a overlaps with a portion of wall panel 200b towards the bottom of wall panel 200a. Bottom wing 11a can be connected to wall panel 200a by fastening bottom wing 11a to panel support 208 and panel connecting support 210 with for example screws or nails.

A door or window can be added into wall panel 200 by cutting the appropriate opening in wall panel 200 and inserting the desired accessory. In some embodiments, wall panel 200 provides sufficient support for the accessory (i.e., window, door) and no additional support needs to be added to wall panel 200.

Additional insulating panels can be added to wall panels 200 by removing interior panel 202, adding additional insulating panels and reinstalling interior panel. In this way, the degree of insulation in building module 10 can be altered at any time, including after the initial construction of building module 10.

An outer covering, such as siding, is attached to panel support 208 and panel connecting support 210 to protect wall panels 200 from the elements and to enclose building module 10. In some embodiments, utilities, such as electric and water, can be run in the space formed by panel support 208, panel connecting support 210, and wings 11 and 13 between second insulation panel 206 and outer covering. Utility accessories such as electrical outlets and light switches for electricity and sinks for water can be added at any time, including after the initial construction. For example, an electrical outlet can be added by cutting the appropriate sized hole in wall panel 200, adding an electrical outlet and wiring the electrical outlet with electrical power.

A wall panel 200 can be repaired or replaced after initial construction by unfastening wall panel 200 from building module 10 and either repairing and reattaching or attaching a new wall panel 200. Wall panel 200 can also be moved. The wall panels 200 form an adaptive wall system which allows removal or repositioning of individual wall panels, before or after the building is completed.

Building codes vary by community. For example, stud requirements in building codes vary by community. To accommodate these differences, modifications can be made to adjust the roof, walls and flooring. For example, additional studs (i.e., panel supports 208), additional rafters and/or floor supports can be added to meet codes. Additionally, insulation can be varied by material and/or depth in addition to alternate inside and outside wall coverings.

FIG. 11 is a schematic top view diagram illustrating two building modules, 10a and 10b, positioned side-by-side as part of a single building system. As shown in FIG. 11,

12

portions of the adjoining walls can be removed and a coupler 110 can be added such that the interior spaces of first building module 10a and second building module 10b are in communication with each other.

FIG. 12 is a schematic top view diagram illustrating two building modules, 10a and 10b, positioned end-to-end. Portions of the outside steel and the adjoining walls (marked in dashed lines in FIG. 12) can be removed so the interior spaces of first building module 10a and second building module 10b are in communication with each other and form a single interior space. Alternatively, the outside steel can be removed and a door installed in one of the adjoining wall panels. In this way, the interior spaces of first building module 10a and second building module 10b are connected but can be portioned separately, for example to control temperature or to reduce sound.

FIG. 13 is a schematic top view diagram illustrating four building modules, 10a, 10b, 10c and 10d, positioned to form a rectangle. Building modules 10a and 10b are positioned end-to-end as described above in FIG. 12. Similarly, modules 10c and 10d are positioned end-to-end. Further, building modules 10a and 10c are positioned side-by-side and building modules 10b and 10d are positioned side by side. Portions of adjacent walls (marked in dashed lines in FIG. 13) can be removed so that the interior of all four modules are in communication with each other and form a single interior space.

FIG. 14 is a schematic top view diagram illustrating six building modules, 10e, 10f, 10g, 10h, 10i, and 10j positioned to form a building system having an interior courtyard. Building modules 10e and 10f are positioned side-by-side. The end of building module 10g connects to the side of building module 10f and the other end of building module 10g connects to the side of building module 10h. The end of building module 10h connects to the side of building module 10i. As illustrated with building module 10j, the building modules can be connected at any location by removal of a wall panel.

The invention of the current application allows one or more wall panels of adjacent walls to be removed. In this way, a number of different and unique floor plans can be created. Further, the current invention allows wall panels to be removed or replaced after the initial build. This allows the overall building to be re-configured (e.g., the removal or addition of walls or portions of walls) even after the initial build. Additionally, the structure/engineering combats deflection of boards in all directions. Meaning, the combination and placement of each set of boards with conjunction with plywood and other parts, combats deflection of the various individual boards as well as pieces.

In some embodiments, all lumber used in the building system and each building module is standard lumber available commercially which eliminates the need to cut lumber to build the module(s). Standard size lumber has been specifically mentioned herein and include the following boards at least in the United States: 2x4, 2x6, 2x12, 4x6, and 6x6.

From the foregoing description, one skilled in the art can easily ascertain the essential characteristics of this invention and, without departing from the spirit and scope thereof, can make various changes and modifications of the invention to adapt it to various usages and conditions.

The invention claimed is:

1. A building module system comprising a building module, the building module comprising:
a base support comprising:

13

a frame having rectangular shape with a first side, a second side, a first end and a second end, the frame formed by a first lengthwise base support connected to a first end of a first cross support and to a first end of a second cross support and a second lengthwise base support connected to a second end of the first cross support and to a second end of the second cross support; 5

a subfloor connected to the frame and extending from the first side to the second side and from the first end to the second end; 10

floor supports positioned above the subfloor, each floor support extending from the first side to the second side of the frame; 15

a first bottom wing having a first side and a second side opposite the first side, the first side of the first bottom wing connected to and extending upwards from the first lengthwise base support of the frame; 15

a second bottom wing having a first side and a second side opposite the first side, the first side of the second bottom wing connected to and extending upwards from the second lengthwise base support of the frame; 20

a plurality of flooring panels positioned above and supported by the floor supports, each flooring panel extending from the first side to the second side of the frame and the flooring panels together extending from the first end to the second end of the frame; 25

a roof support spaced apart from the base support and having a rectangular shape with a first side, a second side, a first end and a second end, the roof support formed by a first lengthwise roof support connected to a first end of a first roof cross support and a first end of a second roof cross support and a second lengthwise roof support connected to a second end of the first roof cross support and a second end of the second roof cross support; 30

a plurality of ceiling panels attached to the roof support; 35

rafter module having a width and connected to the roof support, the rafter module comprising:

a plurality of webs extending in a first direction and spaced apart from one another in a second direction, each web having a top surface, a bottom surface, a first end, a second end and spanning the width of the rafter module; 40

a plurality of chords spaced apart from one another in the first direction and extending in the second direction, wherein each chord is connected to the top surface of each of the webs; and 45

a bottom chord connected to the bottom surface of each of the webs at the second end, the bottom chord creating a slope so that the second ends of the webs are higher than the first ends of the webs, wherein the first direction is perpendicular to the second direction; 50

a first top wing having a first side and a second side opposite the first side, the first side of the first top wing connected to and extending downward from the first lengthwise roof support of the roof support; 55

a second top wing having a first side and a second side opposite the first side, the first side of the second top wing connected to and extending downward from the second lengthwise roof support of the roof support; and 60

14

vertical supports extending vertically between the base support and the roof support and connecting the base support and the roof support;

a plurality of wall panels connected to and extending from the first side of the first top wing to the first side of the first bottom wing and from the first side of the second top wing to the first side of the second bottom wing, a bottom surface of each of the plurality of wall panels resting on at least one flooring panel; and

a plurality of siding panels connected to and extending from the second side of the first top wing to the second side of the first bottom wing and from the second side of the second top wing to the second side of the second bottom wing, wherein the wall panels are spaced apart from the siding panels.

2. The building module system of claim 1 wherein the wall panels include at least a first wall panel and a second wall panel, each of the first wall panel and the second wall panel including:

an interior panel having a top interior panel edge, a bottom interior panel edge, a first side interior panel edge and a second side interior panel edge;

a first insulating panel connected to the interior panel, the first insulating panel having a top first insulating panel edge aligned with the top interior panel edge, a bottom first insulating panel edge aligned with the bottom interior panel edge, a first side first insulating panel edge aligned with the first side interior panel edge and a second side first insulating panel edge aligned with the second side interior panel edge; and

a second insulating panel connected to the first insulating panel, the second insulating panel having a top second insulating panel edge aligned with the top first insulating panel edge, a bottom second insulating panel edge aligned with the bottom interior panel edge, a first side second insulating panel edge not aligned with the first side first insulating panel edge and forming a protrusion, and a second side second insulating panel edge not aligned with the second side first insulating panel edge and forming a notch,

wherein the protrusion of the first wall panel fits within the notch of the second wall panel and a portion of the first wall panel overlaps with a portion of the second wall panel.

3. The building module system of claim 2 and further including a panel connecting support connected to the second insulating panel of the first wall panel and the second insulating panel of the second wall panel.

4. The building module system of claim 2 wherein the first wall panel and the second wall panel are removable in whole.

5. The building module system of claim 2 wherein a window or a door is positioned within the first wall panel and is in communication with the interior panel, the first insulating panel and the second insulating panel.

6. The building module system of claim 1 and further comprising a plurality of rafter modules connected to one another.

7. The building module system of claim 1 and further comprising a second building module connected to the building module.
